ENRIQUE LAZARTE, OF LIMA, PERU, ASSIGNOR TO AEROPLANE DESTROYER COMPANY,
OF LIMA, PERU.

AEROPLANE-DESTROYER.

1,161,778.

Specification of Letters Patent.

Patented Nov. 23, 1915.

Application filed January 12, 1915. Serial No. 1,855.

To all whom it may concern:

Be it known that I, ENRIQUE LAZARTE, citizen of the Republic of Peru, residing at Lima, Peru, have invented new and useful 5 Improvements in Aeroplane-Destroyers, of which the following is a specification.

This invention relates to ordnance and in particular to an aeroplane destroyer.

In firing upon aeroplanes or other moving objects with guns of the well known types, such as are now in use in the European war, it is impossible to keep the piece trained upon the shifting target while estimating the range, the velocity of the target, 15 and the allowance to be made in the sighting on account of the trajectory of the projectile fired and the velocity of the target, particularly when it is desired to fire a number of shots in rapid succession.

It is, therefore, the chief purpose of my 20 invention to provide a destroyer in the form of a machine gun or rifle combined with range-finding and sighting mechanism of a character which will enable the gunner to 25 estimate certain constant factors essential in the aiming at any given target of the nature set forth and then to keep the piece trained properly upon the shifting target throughout the firing of a number of successive 30 shots without making further estimations or mathematical calculations.

A further object of the invention is the 35 provision of a destroyer of this nature which will afford effective cover for the gunner operating the same, and which may be adapted readily for marine use, wherein it may be used just as effectively upon a rolling and 40 rocking ship as upon terra firma.

In accomplishing these objects I propose 45 to utilize the principle of the camera obscura and in fact employ a large camera obscura whose opaque casing is constructed preferably of armor plate so that the gunner may find protection therein from hostile fire. The gun proper is mounted upon the casing 50 and associated with the lens and image-receiving floor surface of the camera in such a manner and by such mechanism that the produced upon the said surface of an aeroplane, balloon, or other target passing through the exterior field of the camera may

be utilized in bringing the line of aim established by the gun sights into coincidence with the proper line of sight or incident ray 55 passing from the target through the camera lens. The image-receiving surface is provided with a diagram which is so correlated with the lens and the gun sighting and adjusting mechanism that the initial estimations and calculations necessary to establish certain factors, which will be constant throughout the subsequent aiming and firing operations, as well as the subsequent changes in the aiming, may be made with direct reference to the image. 60

The specific details of the construction are described in full in the following specific description and are shown in the accompanying drawings in which:

Figure 1 represents a side elevation of the preferred embodiment of the invention; Fig. 2 is a front elevation of the same; Fig. 3 is a vertical sectional view, showing the device in use in firing upon a moving target; Fig. 4 is a horizontal sectional view on line 4-4 of Fig. 3; Fig. 5 is a similar view on line 5-5 of Fig. 3; Fig. 6 is a vertical sectional view through a portion of a modified form of the device; and Fig. 7 is a side elevation of a form of the device for marine use showing the same mounted upon a ship, means being shown for use in tilting the casing.

Referring to the drawings and in particular to Figs. 1 to 5 inclusive, it will be seen that I have constructed the casing 1 of the camera obscura in the form of a dome of armor plate. This dome has a suitable base 2, which is provided with a floor 3 having, 85 in this instance, a plane image-receiving upper surface. The lens 4 of the camera is mounted within the aperture 5 provided centrally within the upper end of the casing 1 in a vertically adjustable holder 6. This 90 lens is of such character that its focal length will bear the proper relation to its distance from the image-receiving surface 3. A yoke member 7 has its bifurcated ends 8 embracing the lens holder 6 and pivotally connected thereto by means of the trunnions 9, whose axis intersects the optical center of the lens. A frame piece 10 in the form of a lever is pivotally connected medially with 95 100

the yoke member 7 by means of a strong pivot member 11, whose axis intersects the axis of the trunnions 9 at right angles thereto and at the point of intersection of the 5 latter with the axis of the lens. The frame piece is thus mounted for free swinging movement. A gun 12 having a barrel 13 is mounted upon the upper end of the frame piece 10 in such a position that the line of 10 aim established by its permanent sights 14 and 15 will intersect the axes of the frame pivots at their common point of intersection with the lens axis. It should be apparent, therefore, that the line of aim will 15 pass through the center of the lens at all times, irrespective of the degree of angular adjustment of the frame piece. In the drawings a machine gun of the mitrailleuse type is shown, but it is to be understood 20 that any convenient form of rifle or cannon may be employed without departing from the spirit of the invention, provided it has means of some sort embodied in its construction for absorbing the recoil so as 25 to obviate undue stress upon the trunnions 9 and the pivot member 11 when the piece is fired. The firing mechanism of the piece is provided necessarily with an extended trigger 16 in order that it may be connected operatively with the firing lever 17, which is 30 pivotally mounted upon the frame piece 10 adjacent to its lower end, by means of a connecting rod 18. The firing lever is provided with a suitable handle 19 which may 35 be grasped by the gunner in discharging the piece. In the preferred embodiment of the invention, the lower end of the frame piece is projected into the dome-shaped casing 1 through an opening 20 therein, which is constructed just large enough to permit the required movement of the frame piece but not enough to affect the shielding efficiency of 40 the casing materially. A needle-shaped pointer 21 is mounted for axial adjustment 45 within a holder 22 provided upon the lower end of the frame piece and is arranged in true alinement with the line of aim of the piece. This pointer is adapted to traverse the image-receiving surface 3 and is adjustable as described in order to accommodate 50 the same to a plane surface.

The image-receiving surface of the camera floor has a diagram delineated thereon with direct reference to the focal length of the 55 lens. This diagram consists of two parts, one of which consists of rectilinear coördinates and the other of concentric circles, both having as a common center a point in line with the axis of the lens. The coördinates and circles of both parts or systems are graduated with reference to the focal length of the lens so that the coördinates may be used in a manner which should be obvious to mathematicians or engineers in 60 determining at a glance the distance of an

aerial object or target whose image is cast upon the surface 3 so as to cover a certain area of the same, and so that the circular system may be used in determining the trajectory of the piece. When the range has 70 been determined by using the coördinates, the velocity of the target may be determined by timing the advance of the image over any convenient distance on the coördinate system. These two factors, the range and velocity of the target, having been determined for any given target which may be passing through the exterior field of the camera, they will remain constant ordinarily 75 throughout the flight through this limited field, especially when the target is near. The characteristic trajectory of the piece for any particular elevation being known, the circular system of the diagram, is graduated so that each division will represent a definite number of points of elevation, the value of each of which will be known to the gunner. From this knowledge, he can calculate 80 mentally the number of points of elevation change in the line of aim, which is fixed 85 with relation to the axis of the gun bore, necessary to hit a stationary target at a given range. In contending with a moving target, however, the velocity of the latter must be considered also and the initial adjustment of the pointer upon the image-receiving surface must be such that the pointer will be located in the path of the image at the proper distance from the point upon the same corresponding to the part of the target 90 it is desired to hit, and that it will be located at the required distance from the center of the diagram to afford the necessary elevation. The use of this diagram and the pointer associated therewith in adjusting the piece for the initial shot should be obvious to any military engineer or gunner, so the mathematics of the operation will not 95 be set forth in detail. When the initial adjustment has been effected properly, the 100 pointer will be moved thereafter along the path of the image so as to precede the latter at the same speed and consequently at the same distance therefrom. It will not be necessary therefore to make any further 105 mathematical computations in connection 110 with the subsequent shot, unless it is found that the shots are not effective and it becomes necessary to make slight corrections to allow for changing atmospheric conditions or the like.

In Figs. 3 and 4 in particular the destroyer is shown in action. t represents the target or objective which is flying in the direction of the arrow a in a path p , represented by dotted lines. i is the image of the target which is cast upon the surface 3 of the camera floor and which travels in the path p' in the direction of the arrow b . Dotted lines $r r r$ represent rays of light 115 120 125 130

passing from three parts of the target through the lens of the camera to the image, and dotted line t' is the trajectory of a projectile fired from the piece and which intersects the path of the target h , where it should hit the target.

In Fig. 6 a slight modification of the construction is disclosed, wherein the major portion of the frame piece 10 extends along the dome-shaped portion of the casing 1 exteriorly thereof, a comparatively long indent extension 23 being provided upon the lower end of the frame piece. This extension bears the pointer 24 and extends into the casing through a horizontally elongated slot 25 which is provided in the casing immediately above the floor of the same. In this instance the slot or opening for the reception of the frame piece extension is positioned so low within the casing wall that the latter is rendered more effective as a shield. In order that the pointer will contact evenly with all parts of the image-receiving surface no matter what the degree of angular adjustment may be, and without it being necessary to adjust the pointer axially for this purpose, the said image-receiving surface may be formed concave, concentric to the optical center of the lens and consequently the center of the pivotal mounting of the frame piece. This construction is shown also in Fig. 6, which illustrates some of the modifications which may be resorted to in practice to increase the efficiency of the destroyer.

In Fig. 7 the camera casing is shown provided with a gimbal mounting whereby the destroyer may be mounted upon a ship of any description for marine use. It is obvious that it will be maintained in an upright position at all times, despite the unsteady movement of the vessel. In this instance, a horizontal ring 26 surrounds the casing and is pivotally connected therewith by means of the trunnions 27. The ring in turn is journaled in the vertical supports 28 upon a diametrical axis arranged at right angles to the axis of the trunnions. The said supports are carried by a suitable base mounted upon the deck or any other convenient part of the vessel. In order that the casing may be adjusted angularly and secured in adjusted position to change the field of fire so as to permit horizontal firing, a hand lever 30 is attached to the ring 26 of the gimbal in radial relation to its axis of pivotal mounting upon the supports 28, and it is provided with any suitable means, such as a pawl and ratchet device, for securing the said ring in its adjusted position for this purpose in fixed relation to the stationary base. The adjustment of the ring is effected by manipulating the hand lever. A certain form of adjusting and securing means is disclosed in Fig. 7 in par-

ticular in use for the purpose just mentioned, but it is to be understood that I do not limit myself necessarily to this particular construction, but may resort to any efficient and readily operable form of mechanism for this use which may appear in practice to be the most suitable expedient.

While the camera is shown in the drawings and described in the specification as being provided with a lens, it is manifest that the lens may be omitted and that the provision of a minute aperture in the casing will serve the same purpose, though imperfectly. It is to secure efficiency of the camera in the very difficult work for which it is intended that I have employed a lens, this being a mere mechanical expedient. In the event that the barrel of the firearm is found to produce a shadow upon the image-receiving surface, the cause may reside in the position of the barrel with relation to the lens. If the barrel is found to be too close to the lens, the lens holder may be adjusted within the casing aperture so as to space the same properly from the barrel of the piece, or the defect may be remedied by substituting a larger lens.

What I claim is.

1. An aeroplane destroyer comprising a camera obscura including a casing having a floor affording an image-receiving upper surface and provided in its upper end with an aperture, a lens mounted within the aperture and being focused upon the said surface, the casing being provided with a second opening, and a firearm consisting of a frame piece pivotally mounted upon the casing upon double pivots having their axes arranged at right angles to each other and intersecting the optical center of the lens, a barrel mounted upon the upper end of the frame piece in alinement with the optical center of the lens, firing mechanism associated with the barrel, the lower end of the frame piece being projected into the casing through the second opening therein, a pointer provided upon this end of the frame piece in alinement with the axis of the barrel of the firearm and adapted to traverse the image-receiving surface, and means for operating the firing mechanism.

2. An aeroplane destroyer comprising in combination a camera obscura consisting of a casing having an aperture therein, a lens mounted within the aperture, the casing having a floor providing an image-receiving upper surface positioned so that the lens is focused thereon, the firearm adjustably mounted upon the casing and having a barrel, means for maintaining the said barrel in alinement with the optical center of the lens irrespective of angular adjustment of the same, firing mechanism associated with the barrel, and means for adjusting the position of the firearm with reference to the

image projected by the lens upon the said surface.

3. An aeroplane destroyer comprising in combination a camera obscura consisting of a casing having a floor affording an image-receiving upper surface, the casing being provided with an aperture in its upper end, a lens mounted within the aperture and being focused upon the said surface, a firearm 10 adjustably mounted upon the casing, and means for adjusting the firearm with respect to the image-producing rays passing through the lens.

4. An aeroplane destroyer comprising a camera obscura consisting of a casing having a floor affording an image-receiving upper surface, the casing being provided with a side opening and with an aperture in its upper end, a lens mounted within the said 15 aperture and being focused upon the said surface, and a firearm consisting of a frame piece pivotally mounted upon the casing, a barrel mounted upon the upper end of the frame piece, firing mechanism associated 20 with the barrel, means for maintaining the barrel in alignment with the optical center of the lens irrespective of the adjustment of the frame piece, the lower end of the frame piece being projected through the side opening 25 in the casing, a pointer provided upon this end of the frame piece in alignment with the axis of the firearm barrel and adapted to traverse the image receiving surface, and means provided upon the lower 30 end of the frame piece for operating the firing mechanism.

5. An aeroplane destroyer comprising a camera obscura consisting of an armored casing having a floor affording an image-receiving upper surface, the casing being provided with a side opening and with an aperture in its upper end, a lens mounted within the said aperture and being focused upon the said surface, and a firearm 40 consisting of a frame piece pivotally mounted upon the casing, a barrel mounted upon the upper end of the frame piece, firing mechanism associated with the barrel, means for maintaining the barrel in alignment with the optical center of the lens irrespective of the adjustment of the frame piece, the lower end of the frame piece being projected through the side opening in the casing, a pointer provided upon this end of the frame piece in alignment with the axis of the firearm barrel and adapted to traverse the image-receiving surface, and means provided upon the lower end of the frame piece 45 for operating the firing mechanism.

6. An aeroplane destroyer comprising a camera obscura consisting of a casing having a floor affording an image-receiving upper surface, the casing being provided with a side opening and with an aperture

in its upper end, a lens mounted within the said aperture and being focused upon the said surface, a firearm consisting of a frame piece pivotally mounted upon the casing, a barrel mounted upon the upper end of the frame piece, firing mechanism associated 70 with the barrel, means for maintaining the barrel in alignment with the optical center of the lens irrespective of the adjustment of the frame piece, the lower end of the frame piece being projected through the side opening in the casing, a pointer mounted upon this end of the frame piece in alignment with the axis of the firearm barrel and being adapted to traverse the image-receiving surface, the said pointer being axially 75 adjustable, and means by which the firing mechanism may be operated.

7. An aeroplane destroyer comprising a camera obscura consisting of a casing having a floor affording a concave image-receiving upper surface, the casing being provided with a side opening and with an aperture in its upper end, a lens mounted within the said aperture and being focused upon the said surface, the surface being arranged 80 concentric to the optical center of the lens, and a firearm consisting of a frame piece pivotally mounted upon the casing upon double pivots having their axes arranged at right angles to each other and intersecting the optical center of the lens, a barrel mounted upon the upper end of the frame piece in alignment with the optical center of the lens, firing mechanism associated with the barrel, the lower end of the frame piece 85 being projected through the side opening in the casing, a pointer provided upon this end of the frame piece in alignment with the axis of the firearm barrel and adapted to traverse the image-receiving surface, and means by which the firing mechanism may 90 be operated.

8. An aeroplane destroyer comprising a camera obscura consisting of a casing having a floor affording an image-receiving upper 110 surface, the casing being provided with a side opening and an aperture in its upper end, a lens mounted within the said aperture and being focused upon the said surface, a firearm consisting of a frame piece 115 pivotally mounted upon the casing, a barrel mounted upon the upper end of the frame piece, firing mechanism associated with the barrel, means for maintaining the barrel in alignment with the optical center of the 120 lens irrespective of the adjustment of the frame piece, the lower end of the frame piece being projected through the side opening in the casing, a pointer mounted upon this end of the frame piece in alignment with the axis of the firearm barrel and being 125 adapted to traverse the image-receiving surface, and means by which the firing mecha-

nism may be operated, in combination with a supporting base, and a gimbal mounting supporting the casing upon the base.

9. An aeroplane destroyer comprising a camera obscura consisting of a casing having a floor affording an image-receiving upper surface, the casing being provided with a side opening and with an aperture in its upper end, a lens mounted within the said aperture and being focused upon the said surface, a firearm consisting of a frame piece pivotally mounted upon the casing, a barrel mounted upon the upper end of the frame piece, firing mechanism associated with the barrel, means for maintaining the barrel in alinement with the optical center of the lens irrespective of the adjustment of the frame piece, the lower end of the frame piece being projected through the side opening in the casing, a pointer mounted upon this end of the frame piece in alinement with the axis of the firearm barrel and being adapted to traverse the image-receiving surface, and means by which the firing mechanism may be operated, in combination with a stationary base, a gimbal mounting supporting the camera casing upon the base, means by which the casing may be tilted with respect to the base, and means for securing the casing in its tilted position.

10. An aeroplane destroyer comprising a camera obscura consisting of a casing having a floor affording an image-receiving upper surface, the casing being provided with a side opening and with an aperture in its upper end, a lens mounted within the said aperture and being focused upon the said surface, a firearm consisting of a frame piece pivotally mounted upon the casing, a barrel mounted upon the upper end of the frame piece, firing mechanism associated with the barrel, means for maintaining the barrel in alinement with the optical center of the lens irrespective of the adjustment of the frame piece, the lower end of the frame piece being projected through the side opening in the casing, a pointer mounted upon this end of the frame piece in alinement with the axis of the firearm barrel and being adapted to traverse the image receiving surface, and means by which the firing mechanism may be operated, a coördinate system being delineated upon the image-receiving surface with the axis of the lens locating its center and being graduated with relation to the focal length of the lens in units representing the range of a target whose image is projected by the lens on the said surface.

11. An aeroplane destroyer comprising a camera obscura consisting of a casing having a floor affording an image-receiving upper surface, the casing being provided with a side opening and with an aperture in its upper end, a lens mounted within the said

aperture and being focused upon the said surface, a firearm consisting of a frame piece pivotally mounted upon the casing, a barrel mounted upon the upper end of the frame piece, firing mechanism associated with the barrel, means for maintaining the barrel in alinement with the optical center of the lens irrespective of the adjustment of the frame piece, the lower end of the frame piece being projected through the side opening in the casing, a pointer mounted upon this end of the frame piece in alinement with the axis of the firearm barrel and being adapted to traverse the image-receiving surface, and means by which the firing mechanism may be operated, a system of concentric circles being delineated upon the image-receiving surface with the axis of the lens as a center and being graduated with relation to the trajectory of the firearm in units representing points of elevation.

12. An aeroplane destroyer comprising a camera obscura consisting of a casing having a floor affording an image-receiving upper surface, the casing being provided with a side opening and with an aperture in its upper end, a lens mounted within the said aperture and being focused upon the said surface, a firearm consisting of a frame piece pivotally mounted upon the casing, a barrel mounted upon the upper end of the frame piece, firing mechanism associated with the barrel, means for maintaining the barrel in alinement with the optical center of the lens irrespective of the adjustment of the frame piece, the lower end of the frame piece being projected through the side opening in the casing, a pointer mounted upon the lower end of the frame piece in alinement with the axis of the firearm barrel and being adapted to traverse the image-receiving surface, and means by which the firing mechanism may be operated, a coördinate system being delineated upon the image-receiving surface with the axis of the lens locating its center and being graduated with relation to the focal length of the lens in units representing the range of a target whose image is projected by the lens on the said surface, a system of circles arranged concentric to the lens axis being delineated also upon the said surface and being graduated with relation to the trajectory of the firearm in units representing points of elevation.

13. An aeroplane destroyer comprising in combination a camera obscura having an image-receiving surface, a firearm adjustably associated with the camera, and a pointer connected with the firearm and being adapted to traverse the image-receiving surface upon adjustment of the former.

14. An aeroplane destroyer comprising in combination a camera obscura having an image-receiving surface, a firearm adjust-

ably associated with the camera and including a barrel, firing mechanism associated with the barrel, and a pointer connected with the firearm in alignment with the axis 5 of the barrel and being adapted to traverse the image-receiving surface upon adjustment of the firearm.

Copies of this patent may be obtained for five cents each, by addressing the "Commissioner of Patents, Washington, D. C."

In testimony whereof I have signed my name to this specification in the presence of two subscribing witnesses.
